CLAIM

The ornamental design for a vacuum regulator, as shown and described.

DESCRIPTION

The rotor is attached to a shaft of the internal combustion engine. It is used to control ignition and cool the engine.

FIG. 1 shows a front view of a vacuum regulator showing my new design;

FIG. 2 shows a rear view thereof;

FIG. 3 shows a top view thereof;

FIG. 4 shows a bottom view thereof;

FIG. 5 shows a left side view thereof;

FIG. 6 shows a right side view thereof;

FIG. 7 shows a top, front and right side perspective view thereof; and,

FIG. 8 shows a top, rear and right side perspective view thereof.
